UNITED STATES PATENT OFFICE.

FREDERIC E. BERTRAND, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR USE IN MAKING SHOES.

Application filed November 10, 1917, Serial No. 201,211. Renewed June 2, 1922. Serial No. 565,396.

To all whom it may concern:

Be it known that I, FREDERIC E. BERTRAND, a citizen of the United States, residing at Lynn, in the county of Essex and State of Massachusetts, have invented certain new and useful Improvements in Machines for Use in Making Shoes; and I do hereby declare the following to be a full, clear, and exact description of the invention, such as will enable others skilled in the art to which it appertains to make and use the same.

This invention relates to machines for use in the manufacture of boots and shoes, and is illustrated as embodied in a channeling machine for fitting soles to be used in such manufacture.

Objects of the invention are to improve the construction of machines of this character to facilitate their conversion for different classes of work, to provide an improved adjustment for the channel knife; to simplify the feed mechanism to permit operation at a higher speed, to prevent operation of the machine where no work is present, and to improve the operation of the machine in other respects as will be explained.

To facilitate conversion of the machine, as when changing from welt to turn work or vice versa, novel means is provided for gaging the edge cut from the top of the sole under control of a presser foot (for welt work), or alternatively for gaging the edge cut from the bottom of the sole or from the work support (for turn work). To facilitate this conversion, an improved construction is provided including a yieldingly-mounted slide carrying a presser-foot (and also, as will be explained, preferably having a knife clamped thereon), a second slide for the edge-knife, and means for connecting and disconnecting the two slides.

To provide a quick adjustment for the channel knife, as is especially desirable in a machine which is thus convertible and as is of utility in channeling machines of other types, the knife carrier is constructed and arranged for movement to tilt the channel knife about the end of its cutting edge, thus causing a single knife to replace the usual series of knives cutting at different angles. Preferably the carrier is also adjustable across the feed, or in the line of feed, or both, to facilitate accurately adjusting the

"lead" of the knife and the width of the 55 between substance formed thereby.

In the preferred embodiment of my invention, the channeling and feeding means includes a device, carrying an intermittently-effective sole-engaging foot, which is 60 mounted for oscillation in a vertical plane about a horizontal axis below the work-support. This not only admits of a very compact and efficient construction, but clears away much of the drive mechanism which 65 overhangs the work-support of previous machines, obstructing the operator's view of the work. I provide operator-controlled means for varying the amplitude of oscillation of this device, to vary the rate at which 70 the work is fed, and in the illustrated machine a novel work-support is provided which includes a sole-engaging member which is reciprocated with the feed foot to co-operate therewith in feeding the work. 75

To prevent the machine from running idle, improved operating and feeding mechanism is provided, including means to prevent the starting of the machine until a new piece of work is inserted, and means for stopping 80 said mechanism when a finished piece of work is removed.

The above and other features of the preferred form of the invention are illustrated in the accompanying drawings, in which 85 Figure 1 is a front elevation of the working head of a channeling machine; Fig. 2 is a plan, Fig. 3 a left end elevation, and Fig. 4 a rear elevation of the machine head shown in Fig. 1; Fig. 5 is a plan view, partly in section, showing more particularly the improved driving mechanism; Fig. 6 is a vertical, sectional view of the machine head taken on the line 6—6 of Fig. 2; Fig. 7 is a vertical, sectional view taken on the line 90 7—7 of Fig. 1; Fig. 8 is a vertical, sectional view taken on the line 8—8 of Fig. 4; Fig. 9 is a plan view on an enlarged scale partly in section, taken on a plane just above the sole supporting table, showing the relation 100 of the sole-engaging tools; Fig. 10 is an enlarged front elevation showing the improved mounting and arrangement of the tools in detail; Fig. 11 is a detail view, in side elevation, of the channel knife block; Fig. 12 is 105 a view of the channel knife block looking from the right in Fig. 11; and Fig. 13 is a detail view, in side elevation, showing the

mechanism for connecting the edge gage with the operating lever of the driving mechanism.

In the illustrated embodiment of the invention the machine is shown as adapted and equipped for channeling turn soles. Referring first more particularly to Figs. 1, 3, 6, 9 and 10, the sole S (Fig. 10) is supported upon a table 20 and is fed past a channel knife 22, and edge knife 24, and a shoulder knife 26, the position of the edge of the sole relative to said knives being determined by an edge gage 28. The depth of the channel cut is gaged by a channel presser-foot or gage 30, the depth of the shoulder cut is gaged by an edge presser-foot or gage 32, and the depth of the edge cut is gaged from the top of the table. The channel presser-gage holds the sole upon the table in advance of the channel knife in the line of feed, and the edge pressure-gage operates in a similar location with relation to both the shoulder and edge knives, although it gages the depth of the cut of the shoulder knife only.

The channel knife 22 is mounted for angular adjustment about an axis passing through the end of its cutting edge in order that the angle of the channel cut may be varied without affecting the width of the between substance or the depth of the channel. The knife is secured in a knife holder 34 (Figs. 11 and 12) by a clamping plate 35 and a cap screw 37. The holder 34 is secured in adjusted position on a knife block 36 by the overlapping head of a screw 39 and a screw 41 passing through an arcuate slot in the knife block and threaded into the holder 34. An arcuate tongue and groove connection between the holder and the block permits radial adjustment of the knife about a center at its cutting point by loosening the screws 39 and 41. By loosening the screw 37 the knife may be removed for sharpening and replaced without disturbing its angular adjustment. The knife block 36 has a dovetailed connection (Fig. 3) with the lower end of a channel knife slide 38 (Fig. 6) through which it may be adjusted toward and from the edge knife to vary the width of the between substance, and it may be locked in adjusted position by means of a bolt 40 threaded into the split lower end of the slide. The channel knife slide 38 is vertically movable in a channel-shaped carrier 42 (Figs. 3, 4 and 6) which is mounted for lateral adjustment, by bolts 44 passed through slots in the carrier, to the front face of a forwardly projecting portion 45 of the machine frame 46. An adjusting screw 48 is mounted in each side of the carrier 42 in position to engage opposite sides of the frame portion 45. By turning these screws the carrier may be adjusted in the line of feed, transversely of the frame. By a suitable adjustment of the carrier 42, the channel knife

slide 38 and its channel knife 22 are bodily shifted in the line of feed, to vary the lead of the channel knife with relation to the edge knife for operating on soles having differently shaped toes.

The channel knife presser-gage 30 (Figs. 3 and 10) has a vertical tongue and slot mounting in a carrier 50 which is secured to the lower end of the channel knife slide 38 by the bolt 40. The presser-gage 30 may be adjusted on the carrier 50 to vary its vertical relation to the channel knife by means of an adjusting screw 52 which has its head rotatably mounted in the carrier 50 and is threaded into the upper end of the presser-gage 30, said gage being locked in adjusted position on the carrier 50 by a headed screw 53. The channel knife 22 and presser-gage 30 are yieldingly held in working position relative to the sole on the table 20, by means of a compression spring 54, (Figs. 3 and 6) which is mounted between the upper end of the slide 38 and an adjusting screw 56 mounted in a yoke 58 formed on the upper end of the carrier 42. With this construction the pressure on the sole by the presser-gage 30 may be altered by varying the tension of the spring 54. The depth of the channel cut is determined, as usual, by the distance the cutting edge of the channel knife projects below the sole-engaging face of its presser-gage. A lug 60 projects forwardly from the upper end of the slide 38, and an adjusting screw 62, threaded therein, is arranged to engage an underlying flange on the carrier 42. The screw 62 limits the lowermost position which the presser-gage and channel knife may occupy with relation to the table, and prevents the channel knife from coming into contact with the face of the table when there is no work in the machine.

The edge knife 24, best shown in Figs. 4, 6, 8 and 9, is mounted in a carrier 64 which is attached to the lower end of an edge knife slide 66 at its rear side. The slide 66 is mounted in a vertical guideway in the machine frame 46 and is held in position by a cover plate 67 (Fig. 8). The edge knife is locked in position in the carrier 64 by a pair of set screws 68, which permit its adjustment in the carrier for wear. To vary the distance of the bottom of the edge cut from the lower or grain face of the sole the edge knife carrier 64 may be adjusted vertically on the slide 66 by a thumb screw 70 which is threaded through a lug at the upper end of the carrier 64 and has a flanged head which fits into a slot in the slide 66. The carrier 64 is locked in adjusted position by means of a screw 72 which passes through a vertical slot in the carrier and is threaded in the slide 66. The construction just described provides for the advantages described in my prior Patent No. 1,030,703,

dated June 25, 1912. A lug 74 is formed on the rear side of the upper end of the slide 66 and rests upon an abutment 76 formed on an adjusting bolt 78 which is threaded into 5 a flange formed at the upper edge of the cover plate 67. The adjusting bolt 78 extends above the lug 74 and a strong compression spring 79 is held between the upper face of the lug and a nut 80 on the upper 10 end of the bolt. Thus the edge knife, by means of the strong spring 79, is held firmly in working position with relation to the sole on the table 20, such position being determined by the engagement of the lug 74 with 15 the abutment 76, but it is also yieldingly held so that it can be withdrawn from the table to insert new work.

The edge presser-gage 32 is located above the table directly in front of the edge and 20 shoulder knives (Figs. 8 and 9). The gage 32 is adjustably mounted, as usual, on the lower end of a presser-gage slide 82 which is mounted independently of the edge knife, being held in position in a slot in the frame 25 46 by a cover plate 83 (see also Fig. 1). A lug 84 is formed at the front of the upper end of the slide 82 and rests on an abutment 86 formed on an adjusting bolt 88 which is threaded into a flange formed on the upper 30 edge of the cover plate 83. The adjusting bolt 88 passes through and extends above the abutment 84 and a compression spring 89, weak as compared with the edge knife spring 79, is held between the upper face 35 of the lug and a nut 90 threaded on the upper end of the bolt. With this construction the edge presser-gage is held yieldingly in working position upon the sole on the table and when there is no sole in the machine its 40 lowermost position is determined by the engagement of the lug 84 with the abutment 86. Figs. 7 and 8 show the parts all in operative position but the sole is omitted in order to avoid confusion. Patents Nos. 1,236,660 45 and 1,236,661, dated August 14, 1917, and granted on applications filed by the present inventor describe a channeling machine in which three, instead of the usual two, knives are employed, namely, channel and shoulder 50 knives which are gaged for depth from the upper surface, or flesh side, of the sole and an edge knife which is gaged from the opposite, or grain side, of the sole. The machine of the present invention embodies substantially like mechanism. The shoulder knife 55 26 (Figs. 8 and 9) is adjustably mounted in a slot in the side of the presser-gage 32 and is locked in position by a cap screw 92 and clamp plate 93. The cutting edge of the shoulder knife makes a V-shaped cut, the depth of which is measured from the upper side of the sole by the presser-gage 32 and is preferably of the same depth as the channel 60 cut. With this construction the presser-gage 32 will hold the sole down on the table for both the edge and shoulder cuts. The shoulder cut for a turn sole is measured from the upper side of the sole, since the gage 32 and shoulder knife are secured together, but the edge cut is measured from the lower side of the sole, or the surface of the table, since the gage 32 yields independently of the edge knife and the edge knife is fixed in vertical position during the operation of the machine by the strong spring 79. 70 This construction insures that the edge of a turn sole will be of uniform thickness and the shoulder will have a uniform depth, whether or not the sole thickness varies from one end to the other, as explained more fully 80 in said prior patents.

Channeling machines for operating on welt insoles are distinguished from those for operating on turn soles by the fact that in a welt machine the vertical position of the edge knife is variable and is determined by the position of the edge presser gage with which it is rigidly connected, while in a turn machine the vertical position of the edge knife is fixed and the edge presser gage is 90 freely movable with relation to the edge knife. 95

In channeling welt insoles the depth of both the channel and edge cuts are gaged from the upper, or flesh, side of the sole. As the majority of welt insoles are fitted with a channel and an edge slit which form a flap and a parallel outer marginal lip, a shoulder knife is not required. To adapt the machine for both welt and turn work the edge knife slide 66 and the edge presser-gage slide 82 are connected together, and arranged so that they will move independently of one another for turn work or may move in unison for welt work. To this end 100 a sleeve 94 (Fig. 8) is formed on the upper end of the edge knife slide 66 and a bushing 96 is slidably mounted therein. An adjusting screw 98 is threaded in the bushing and has a reduced portion at its lower end which is threaded into a rearwardly projecting lug 100 formed on the upper end of the edge presser-gage slide 82. The sleeve 94 is split and is provided with a locking bolt 102 by which it may be clamped to the bushing 96. To adapt the machine for channeling welt insoles the shoulder knife 26 is removed from the edge gage 32, a plain edge knife is substituted for the edge knife 24 as 110 the indented corner to receive the shoulder knife is no longer needed, and the bushing 96 is clamped in the sleeve 94. It is also preferable to remove the spring 89 or to replace it with a weaker spring so that the operation of the slides will be taken care of by the spring 79, which should be weakened by expansion to equal the strength of the channel knife slide spring 54. The thread 115 on the portion of the adjusting screw 98 which engages the bushing 96 has a different 120 125 130

pitch from the thread which engages the lug 100, so that by adjusting the screws 98, when the bushing is locked in the sleeve 94, the vertical relation of the edge presser-gage to the edge knife may be varied, and hence the depth of the edge cut from the flesh side of the sole altered.

The table 20 (Figs. 1, 6 and 8) is formed on the upper end of a tubular shank 104, 10 slidably mounted in a bore in a bracket 106, which is attached to the frame 46 by a pair of bolts 108. The hand lever 109 for adjusting the table in the bracket 106, to position soles of different thickness with relation to the channeling devices and the treadle operated toggle links 110 and 112 (Figs. 1, 13 3 and 4) with the tension spring 114 connected between the machine frame and the toggle for lowering, raising and locking the 20 table in its sole supporting position, all have substantially the same construction and mode of operation as that illustrated in the re-issue patent to Adam H. Prenzel, No. 13,375, dated February 27, 1912, and, since these 25 features form no part of the present invention they will not be described further.

The edge gage 28 is located above the table 20 in advance of the channeling devices in the line of feed to position the sole for 30 the channeling cuts. As is well known to those skilled in the art, the width of the feather or "edge" of both welt insoles and turn soles varies and, therefore, it is desirable to adjust the edge gage transversely of 35 the line of feed to vary, as may be desired, the position of the sole with relation to the channeling devices. The edge gage 28 is adjustably mounted in a carrier 116 (Figs. 5, 7, 9, and 10) which is pivotally mounted, 40 for a purpose to be later described, on the upper edge of an adjusting slide 118. The slide 118 has a dove-tail connection with a block 120 which is fixed to the table shank 104 by means of a bolt 122. To adjust the 45 slide 118 transversely of the line of feed to vary the position of the edge gage, a slot 124 (Fig. 7) is formed in the lower face of the slide and receives a block 126, which is loosely carried by an eccentric stud 128 50 formed at the upper side of the head 131 of an adjusting shaft 130. The head of the shaft is rotatably mounted in a plate 132 secured to the lower edge of the block 120. The shaft 130 is rotated to shift the slide 55 118 by a hand lever 134 which is pivoted to a bracket 136 secured to the lower end of the shaft. To lock the slide 118 in adjusted position a pair of pawls 138 (Figs. 3, 5 and 7) are pivoted to the bracket 136 60 and arranged to engage successively first a lug 139 on the plate 132, then a notch 140 in a plate 141 adjustably secured to the lower side of the plate 132, then a notch 142 in a similar plate 143 and finally an adjustable 65 stop screw 144 mounted in the plate 132.

From an inspection of Figs. 5 and 7 it will be apparent that the handle 134 may be locked in four different positions to produce the four variations in the width of feather commonly employed in channeling welt in- 70 soles. As the edge gage 28 is adjustably secured on the carrier 116 by the screw and slot connection 117 and the plates 141 and 143 are adjustably secured to each other and to the fixed plate 132 by screws 133, 75 these four positions of the edge gage may be varied as the work may require. The pawls 138 are yieldingly held in engagement with the notches 140 and 142 by means of spring-pressed plungers 148 which are mounted in 80 the bracket 136 in position to engage tails on the pawls. To release the pawls from the notches in order to permit adjustment of the slide 118, abutment screws 150 are mounted in the lower side of the hand lever 134 in position to engage the tails of the pawls opposite the plungers 148, so that when the hand lever is depressed the pawls will be lifted out of the notches and the shaft 130 may be rotated. With this construction the edge 85 gage and its adjusting mechanism will be moved upwardly and downwardly when the table shank 104 is operated by the toggle 110—112, and the edge gage will always 90 maintain its working position relative to the 95 surface of the table 20.

A four motion feeding device is provided to draw the sole against the cutting edges of the knives to produce the various cuts. The feeding device consists of a feed foot 100 160 (Figs. 6, 7, 8 and 9) for engaging the flesh side of the sole, and a feed slide 154 mounted to slide in the table 20, for engaging the grain side of the sole. The feed foot has four motions, which comprise a downward stroke to clamp the sole against the feed slide, a forward stroke away from the cutting knives to draw the sole against the knives, an upward stroke to release the sole, and a return stroke preparatory for the next 105 feeding operation, while the feed slide has merely a reciprocating motion which occurs during the feed and return strokes of the feed foot. The feed foot is secured to the end of an arm 161 extending forwardly from the upper end of a vertical slide 162 and is arranged to reciprocate in the line of feed. The slide 162 has a dovetail mounting (see Fig. 5) in a carrier 164, which has a horizontal stud 166 at its lower end (Figs. 6 and 110 7) pivotally mounted in the lower part of the frame 46. To oscillate the carrier 164, to move the feed foot 160 toward and from the cutting edge of the knives, a link 168 is pivotally connected between the carrier and a block 170, which is slidably mounted in a slotted crank 172. The crank 172 is pivoted at its lower end to a rearwardly projecting bracket 174 on the frame 46, and an eccentric rod 176 is connected between the 115 120 125 130 135 140 145 150 155 160 165 170 175 180

upper end of the crank and an eccentric 178 formed near the left-hand end of a driving shaft 180.

The feed slide 154 extends entirely across the table 20 (see Figs. 5 and 8) and its width is sufficient to engage a comparatively large portion of the grain face of the sole. To reciprocate the feed slide simultaneously with the forward and return strokes of the feed foot 160, the feed slide is connected with the carrier 164 by a link 182 (Fig. 8) which has one end loosely mounted on a stud 184 projecting downwardly from the feed slide and the other end rotatably mounted in a boss 186 formed on the front side of the carrier.

The vertical movement of the feed foot 160, into and out of gripping engagement with the sole, is obtained by a vertical reciprocation of the slide 162. In order that the feed foot may accommodate itself to variations in the thickness of the work and to avoid excessive pressure thereon, the feed foot is brought yieldingly into engagement with the sole. The movement of the foot 25 away from the sole, however, is positive. The vertical movement of the slide 162 is produced by an eccentric 188 on the end of the shaft 180 connected by an eccentric strap 190 with the block 192. A rod 194 is pinned to the block 192 and mounted to slide in bearings 200 formed on the slide 162. A spring 202 interposed between the block and the lower bearing 200 transmits a yielding downward movement to the slide under the action 30 of the eccentric 188, so that the slide moves downwardly until the feed foot engages the sole after which the spring 202 absorbs the excess movement. It is desirable that the vertical position of the feed foot 160 shall be capable of adjustment for variation in the thickness of the soles to be operated upon in order that the foot may always engage the sole at about one half of its downward movement. To provide this adjustment the lower end of the rod 194 is threaded and provided with lock nuts 195 which bear upon the under side of the lower bearing 200 when the presser foot is raised from the work. By adjusting these nuts the vertical relation of the block 192 and the slide 161 may be varied as required. When the nuts are screwed up to raise the feed foot, the spring 202 will be compressed to a greater extent, thereby increasing its strength, which is desirable, as a greater spring pressure of the feed foot is required for thick soles than for thin ones. On the upward movement of the eccentric the spring 202 will expand until the nuts 195 engage the lower bearing 200 after which feed foot will be positively lifted from the sole.

By having the large surface of the feed slide 154 in engagement with the sole while the slide is positively moved in feeding the sole, the face of the feeding foot 160

which engages the sole may be comparatively smooth and still effect a positive feeding of the sole. This is especially advantageous because such a feed foot does not mutilate the substance on which it acts. As 70 the channel presser gage 30 and edge presser gage 32 are not used for the purpose of feeding the sole, they may have a long bearing upon the sole across the line of feed (see Fig. 9) and be under a comparatively light 75 spring pressure which facilitates turning the sole when channeling around the curved portions, particularly at the toe. Since the feed slide remains in contact with the sole on its return stroke it tends to slightly withdraw 80 the sole from the knives. This is advantageous, as the sole will have an initial movement on the next feed stroke before it is brought into engagement with the cutting edges of the knives which reduces the cutting strain on the knives and permits a 85 higher speed of operation.

Although a high rate of feed is desirable and preferable along the shank and the fore-part of the sole where the edge is comparatively straight, it is difficult to guide the sole as it is being cut around the toe. It is desirable, therefore, that the speed of the feed of the work may be varied in order to 90 secure the best character of channeling. To vary the speed of the feeding devices the block 170 (Fig. 7) is slidably mounted in the slotted crank 172, and is arranged to be moved toward and away from the pivot of the crank to decrease or increase the 95 length of feed step and consequently the speed of the feed. To this end the block 170 is connected by a depending link 206 with the outer end of a lifting lever 208, which is pivoted on a pin 210 (Fig. 7) 100 mounted near the base of the frame 46. A torsion spring 212 is connected between the lever 208 and pin 210 and acts to hold the slide block in its uppermost position, which 105 position is determined by the engagement of a set screw 214 (Figs. 1 and 7) mounted in a rearwardly projecting arm 216 on the lever, with a lug 218 formed on the frame 46. The lowermost position of the slide block 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860

The feeding devices are stopped to permit the channeled sole to be removed and are again started when a new sole is presented to the channeling devices. To insure a higher speed of operation, both the starting and the stopping of the feeding devices are arranged to be automatically controlled by the vertical movement of the work table 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860

when soles are entered and removed. To this end the driving shaft 180, for operating the feeding devices, is driven by a friction clutch, which consists of a belt driven pulley 224, loosely mounted on the shaft, and a clutching member 226 mounted to rotate with the shaft (Figs. 1, 2, 4 and 5). The clutching member 226 has a conical friction face 228 at one end of the central hub, 5 adapted to fit in a conical recess 230 in the pulley 224, and a friction braking face 232 at the other end of the hub, adapted to engage a corresponding braking face 234 formed on the frame 46. The clutching member is slidably mounted on a sleeve 236 fixed on the driving shaft, and is held for 10 rotation with the sleeve by a spline 238 (dotted lines Fig. 5). A compression spring 240, surrounding the sleeve 236 within the clutching member, is confined between a flange 242 on the clutching member and a flange 244 on the sleeve, and normally acts 15 to hold the clutching member in a driving engagement with the pulley 224.

25 To shift the clutching member into and out of driving engagement with the pulley 224, a cam face 248 (Figs. 1, 4 and 5) is formed on the clutching member at the end of its central hub. A roll 250, carried on the 20 upper end of shifting lever 252, (Fig. 1) pivoted on a boss 254 projecting from the frame 46, is in operative relation with the cam face 248. The lower end of the lever 252 is connected with one link 256 of a 25 locking toggle 256—258, and the other link 258 of the toggle is pivotally connected to the front of the frame 46. Locking lugs 260 and 262 are formed on the ends of the toggle links 256 and 258 respectively in a 30 position to lock the toggle when its knuckle is moved slightly beyond the position necessary to straighten the toggle. A coil spring 264, connected between the toggle links, tends to hold the locking lugs in engagement 35 with one another when in the position just described. An adjustable link 266 is connected between the toggle link 258 and the rear end of a connecting lever 268, which is pivoted on the front of the frame 46. The 40 forward end of the connecting lever is provided with a throat (Figs. 1, 5 and 13) formed by the upper face of a lug 270, at the bottom edge of the lever, and the lower end of a screw 272 threaded into a lug on the upper edge of the lever overhanging the lug 270. The throat is adapted to receive an arm 274 projecting rearwardly from the pivoted edge gage carrier 116. This form 45 of connection between the edge gage carrier and the connecting lever 268 permits the edge gage to be freely adjusted transversely of the line of feed as may be desired. To support the arm 274 during its vertical movement when actuating the connecting lever, a lug 276 formed on the upper edge of

the edge gage slide 118 projects over the arm at the time it is in the throat of the connecting lever.

With the construction just described it will be seen that the clutching member 226 70 will be moved into and out of clutching engagement with the pulley 224, when the table 20, and consequently the edge gage carrier, is moved upwardly and downwardly. When the table is moved upwardly the toggle 256—258 will be broken, as shown in Fig. 1, and the roll 250 will be moved out of engagement with the cam 248, permitting the compression spring 240 to move the clutching member into engagement with the pulley 224. When the table is moved downwardly the toggle is straightened and locked, and the cam roll 250 is moved a distance to the left, (Fig. 1) into position to engage the rise of the cam 248 which is so positioned with reference to the cycle of the machine that it will engage the roll 250 and the clutch member 226 will be moved to the left, to apply the brake and stop the machine, at the time when the feed foot 160 is 80 lifted from the sole. As the feed foot is at its greatest elevation at 180° from the positions shown in Figs. 7 and 8, the machine will stop with the feed foot about midway of its idle or return stroke. The locking of the toggle in straightened position holds the clutching member disconnected from the driving pulley until the toggle is again broken by an actuation of the connecting lever through an upward movement of the work table.

As heretofore described, the work table is normally held in its upper or working position by the spring 114 (Fig. 1) the arrangement being such that when the foot treadle is released the table will be automatically raised by the spring. To prevent the work feeding devices from being set into operation when the work table is raised in this manner and there is no sole thereon, the actuation of the driving mechanism by the upward movement of the table is controlled by a movement of the edge gage. The edge gage carrier 116 may be rotated on its pivot with relation to the table to bring the edge gage into a sole guiding position or a sole detecting position. When the edge gage is in its sole guiding position the arm 274 on the edge gage carrier is held in the throat of the connecting lever 268, at which time a movement of the table will act to either start or stop the driving mechanism. When, however, a sole is removed from the table the edge gage is permitted, as will presently be explained, to advance across the table under the influence of a spring pressed plunger 280 (Fig. 7) which is carried by the lug 276 and bears on the outer side 120 of the arm 274. With the arm 274 discon-

nected from the connecting lever 268 the table may be freely moved up and down without affecting the driving mechanism of the feeding devices.

5 To start the machine for channeling a sole the operator places the sole on the table while it is held in lowered position, and pushes the edge of the sole against the edge gage to rotate the edge gage from the 10 detecting position into the sole guiding position. Then as the table is moved upwardly to present the sole to the channeling devices, the edge gage will be locked in a sole guiding position by means of a spring- 15 pressed plunger 282 (Figs. 1 and 10) which is mounted in a boss formed on the lower side of the cover plate 83 and arranged to engage a groove 284 (Fig. 5) formed for its reception in the arm 274. While the 20 table is being moved down to permit removal of a sole the plunger 282 will follow down with the arm 274 and retain the edge gage in guiding position until the toggle 256— 25 258 has been straightened. Thereafter, a further downward movement of the table will draw the arm 274 below the plunger 282 and permit the plunger 280 to force the arm 274 out of the throat of the connecting lever and move the edge gage into 30 detecting position.

To facilitate the removal of the sole from the channeling devices, it is desirable to lift the channeling devices away from the sole as well as to lower the work table. To 35 accomplish this a horizontal link 284 (Figs. 1, 4, and 6) is connected between an arm 285 at the upper end of the table toggle link 110 and the vertical arm of a bell crank 286, pivoted to the rear side of the 40 frame 46. An adjustable link 288 is connected between the horizontal arm of the bell crank 286 and an arm 290 (Fig. 2) on a yoke 292, which is loosely pivoted on a shaft 294 above the frame 46 journaled between a pair of arms 296 extending outwardly and upwardly from the frame. The 45 yoke carries a series of three adjustable screws 298, which are located above the rear ends of a series of levers 300, 302 and 50 304, loosely pivoted on the shaft 294, between the arms of the yoke. The forward end of the lever 300 engages the lug 74 (Fig. 8) on the edge knife slide 66. The forward end of the lever 302 engages a lug 306 (Fig. 56) formed on the rear side of the channel knife slide 38. The forward end of the lever 304 engages the lug 84 on the presser-foot slide 82. The adjustable screws 298 may be withdrawn so that they will not 60 engage the levers 300, 302 and 304, and in this way any one or all of the levers may be operated, to lift the tool slides with which they engage, when the yoke 292 is oscillated by the downward movement of 65 the work table.

In channeling different types of soles it is requisite to remove and reinsert one or another of the knives at certain points along the sole edge during the continuous feed of the sole, as is well known to those skilled in the art. To accomplish this a second yoke 308 (Figs. 2 and 6) is pinned to the shaft 294 within the yoke 292. A series of three adjustable screws 310 are mounted in the yoke 308 above the rear ends of the levers 300, 302 and 304. To operate the yoke 308 an arm 312 (Figs. 1 and 2) is pinned to the front end of the shaft 294 and arranged to be connected with a foot treadle by a rod 314. The adjustable screws 310 may be withdrawn to prevent engagement with the levers 300, 302 and 304, so that any one, or all, of the slides 38, 66 and 82 may be raised by depressing the treadle connected to the rod 314.

The operation of the machine will be apparent from the foregoing description, and it will only be necessary to conclude with a reference to some of the more important advantages of the construction hereinbefore described.

The feature of interchangeability from welt work to turn work is a new and important development in machines for channeling soles; and in this connection ability of the operator on welt work to test the thickness of the lip being cut, on the first sole fed from any stint of work, while the machine is working, is exceedingly valuable. This is accomplished by adjusting the screw 98 (Fig. 8) after the sleeve 94 has been tightened on the bushing 96, which screw, (see Fig. 2) is within easy reach of the operator. Such an adjustment varies the vertical relation of the edge presser gage 32 to the edge knife 24, and consequently the depth of cut of said knife. This feature is particularly advantageous in gem insole work. Another important feature is the location of the feed foot 160 on the between substance and back of the cutting edges of the knives (see Fig. 9). This location prevents any disturbance of the flesh on the sole where the cuts are to be made, and leaves a free space at the front of the knives for broad channel and edge gages which will iron down the flesh on the sole across the full width of the portion to be cut. The location of the feed foot is such that the greatest pressure is applied back of the cutting edges of the knives, gives a greater freedom to turn the sole during the feed and produces more even work. The automatic starting mechanism forces the operator to begin the cuts at the breast of the heel because he must place the sole under the presser gages before the feed foot will engage the sole to feed it. This eliminates cutting-in from the edge of the heel seat and avoids weakening this portion of the sole. By utilizing the edge gage to start the machine,

the starting may be accomplished by a sole of any thickness without adding more friction or spring pressure on the sole, as is necessary if a clutch tripping feeler is utilized to engage the face of the sole.

In the foregoing description and in the following claims, the term "channeling devices" is used, which is understood to refer to the channel knife, edge knife, and shoulder knife, and their co-operating presser-gages. The term does not necessarily refer to the combination of all of these knives and presser-gages, but is intended to apply also to channeling devices for different types of sole feeding machines which may include any one of the knives and its presser-gage, or a combination of any number of the knives with their presser-gages.

While the particulars of construction herein set forth are well suited to the particular machine selected for the purpose of illustration and explanation, it is to be understood that these particulars are not essential, since they may be variously modified within the skill of the artisan without departing from the true scope of the actual invention as defined in the following claims:

What is claimed as new, is:

1. A channeling machine having, in combination, an edge knife slide movably mounted on the frame and provided with an edge knife, an edge presser gage slide movably mounted on the frame and provided with a presser gage, and connections between said slides whereby they may move independently of one another or whereby the position of the edge knife slide is controlled by the position of the edge presser gage slide.

2. A channeling machine having, in combination, a work support, an edge knife and a slide carrying said knife movably mounted on the frame and adjusted to gage the cut from the grain side of the sole, a second slide carrying a shoulder knife movably mounted on the frame, an edge presser gage also carried on the second slide adjusted to gage the shoulder cut from the flesh side of the sole, and connections between said slides whereby the depth of both the shoulder and edge cuts may be gaged by said edge presser gage from the flesh side of the sole.

3. A channeling machine having, in combination, an edge knife support, an edge knife carried thereby, a yieldingly mounted edge presser gage support movable independently of the edge knife support, an edge presser gage carried thereby, and means for connecting said supports to cause them to maintain a fixed relation.

4. A channeling machine having, in combination, an edge knife support, an edge knife carried thereby, a yieldingly mounted edge presser gage support movably independently of the edge knife support, an edge presser gage carried thereby, means for con-

nnecting said supports to cause them to maintain a fixed relation, and means for adjusting the gage relatively to the knife when so connected.

5. A welt and turn channeling machine having, in combination, a frame having a plurality of vertical ways formed therein, a work-support on the frame, a presser-gage and a presser-gage slide yieldingly mounted in one of the ways, a knife also carried by the presser-gage slide, an edge-knife and an edge-knife slide in another of said ways, and means to connect the slides to gage the edge cut from the presser-foot or to disconnect them to gage it from the work-support. 80

6. A welt and turn channeling machine having, in combination, a frame having a plurality of vertical ways formed therein, a work-support on the frame, a presser-gage and a presser-gage slide yieldingly mounted in one of the ways, a knife controlled by the presser-gage, an edge-knife and an edge-knife slide in another of said ways, and means to connect the slides to control the knives in unison from the presser-foot or to disconnect the slides to gage the edge cut from the work-support. 90

7. A welt and turn channeling machine having, in combination, a vertically-movable yieldingly-mounted slide, a presser foot carried thereby, a knife controlled by the presser foot, a second vertically movable slide and an edge knife carried thereby, means normally holding the second slide stationary to gage the edge cut from the bottom of a sole, and means for connecting it to the first slide to gage the edge cut from the top of the sole. 100

8. A welt and turn channeling machine having, in combination, a channel knife gaged from the top of a sole, an edge knife and means to gage its cut from the bottom of a sole, auxiliary alternatively-operable means for gaging the edge cut from the top of the sole in unison with the cut of the channel knife, a slide carrying the channel knife and movable toward and from the edge knife, and a knife holder carrying the channel knife and mounted on the slide. 110

9. A welt and turn channeling machine having, in combination, a channel knife and means to gage its cut from the top of a sole, an edge knife and means to gage its cut from the bottom of a sole, and auxiliary alternatively-operable means for gaging the edge cut from the top of the sole in unison with the channel knife, said first means comprising a slide carrying the channel knife and movable toward and from the edge knife, and a knife holder carrying the channel knife and mounted on the slide in such a manner as to be adjustable thereon to tilt the knife about its cutting edge to vary the angle of its cut. 120

10. A channeling machine, having, in com-

- bination, a channel knife, an edge knife, a channel knife slide yieldingly mounted in the frame, and means for adjusting said slide on the frame in the direction of the feed of the sole to vary the lead of the channel knife relative to the edge knife.
11. A channeling machine having, in combination, a channel knife, an edge knife, a support for the channel knife, a knife block on said support adjustable toward and from the edge knife, and a knife holder on said block angularly adjustable about an axis passing through the end of the cutting edge of the channel knife.
12. A channeling machine having, in combination, a channel knife, an edge knife means for relatively adjusting said knives across the line of feed to vary the thickness of the between substance, and means to adjust the channel knife, to vary the angularity of the channel cut, about an axis passing through the free extremity of the cutting edge of the channel knife.
13. A channeling machine having, in combination, a work-support, a fixed guideway, an edge knife movable in said guideway, a channel knife, a knife carrier for the channel knife constructed and arranged for adjustment to tilt the knife about the end of its cutting edge, a yieldingly-mounted vertically-movable slide carrying the knife carrier, and a presser foot mounted on the slide.
14. A channeling machine having, in combination, a work support, a fixed guideway, an edge knife movable in said guideway, a channel knife, a knife carrier for the channel knife constructed and arranged for adjustment to tilt the knife about the end of its cutting edge, and a vertically-movable slide carrying the knife carrier and yieldingly urged toward the work-support.
15. A channeling machine having, in combination, a work-support, an edge knife, a channel knife, a knife carrier for the channel knife constructed and arranged for adjustment to tilt the knife about the end of its cutting edge, and connected slides carrying the channel knife carrier, one mounted for movement in a vertical direction and the other in a horizontal direction.
16. A machine as defined by claim 15, in which the slides also carry a channel-knife presser foot and the vertically-movable slide is yieldingly urged downwardly toward the work.
17. A channeling machine having, in combination, a horizontal work-support, a fixed support having a vertical way substantially aligned with the work-support, a vertical slide in the way, a spring urging the slide toward the work-support, a knife carried by the slide and mounted for angular adjustment about the end of its cutting edge, and a presser foot on the slide and mounted for vertical adjustment.
18. A channeling machine having, in combination, a horizontal work-support, a fixed support having a vertical way substantially aligned with the work-support, a vertical slide in the way, a spring urging the slide toward the work-support, and a knife carried by the slide and mounted for angular adjustment about the end of its cutting edge.
19. A channeling machine having, in combination, a channel knife, a knife holder and means to clamp the knife thereto, a support and a block adjustably secured thereto by a dovetail joint for sliding adjustment thereon, and means for securing the holder to the block including means for guiding the holder to tilt the knife about the end of its cutting edge, and means to clamp the holder to the block to hold the knife in adjusted position.
20. A channeling machine having, in combination, a channel knife, a knife holder and means to clamp the knife thereto, a support and a block adjustably secured thereto by a dovetail joint for sliding adjustment thereon, means for securing the knife holder and the block adjustably together including a co-operating arcuate rib and recess curved about an axis passing substantially through the end of the cutting edge of the knife, and an arcuate slot and a clamp screw passing through it to hold the knife in adjusted position.
21. A channeling machine comprising, in combination, a channel knife and a carrier therefor, a support for the carrier, means angularly to adjust the carrier on the support about the end of the cutting edge of the knife, and means to adjust the support in the line of feed of work operated on by the knife.
22. A channeling machine having, in combination, means for supporting and positioning and feeding a sole, a channel knife to operate on the sole, and means angularly to adjust the knife about the end of its cutting edge and to adjust it in the line of feed of the sole.
23. A channeling machine having, in combination, means for supporting and positioning and feeding a sole, a channel knife to operate on the sole, and means angularly to adjust the knife about the end of its cutting edge and to adjust it across the line of feed of the sole in different positions of angular adjustment without varying the extent to which it is permitted to penetrate the sole.
24. A channeling machine comprising, in combination, a horizontal support for a sole, oscillating means intermittently effective for feeding a sole thereover, an edge knife, a channel knife opposite the edge knife, and means for adjusting the channel knife angularly about the end of its cutting edge.
25. A channeling machine having, in com-

- bination, a channel knife, a carrier therefor, and connected slides supporting the carrier, one slide being movable vertically and yieldingly urged downwardly against the work and the other slide being movable horizontally and adjustable to vary the position of the channel knife relatively to the edge of the work.
26. A channeling machine having, in combination, a channel knife, a carrier therefor, and connected slides supporting the carrier, one slide being movable vertically and yieldingly urged downwardly against the work and the other slide being movable horizontally and normally held against horizontal movement to determine the position of the knife.
27. A channeling machine having, in combination, a channel knife, a presser foot therefor, and connected slides supporting the knife and presser foot, one slide being movable vertically and yieldingly urged downwardly against the work and the other slide being movable horizontally and adjustable to vary the position of the channel knife relatively to the edge of the work.
28. A channeling machine having, in combination, a channel knife, a presser foot therefor, and connected slides supporting the knife and presser foot, one slide being movable vertically and yieldingly urged downwardly against the work and the other slide being movable horizontally and normally held against horizontal movement to determine the position of the knife.
29. A channeling machine having, in combination, a support having a vertical way formed therein, a vertical slide in the way, a channel knife and a presser foot both adjustably clamped to the slide, a spring urging the slide downward against the work, and means for feeding the work past the knife to cause the knife to cut the work.
30. A channeling machine having, in combination, channeling devices, a sole support, sole feeding means, mechanism for operating the feeding means, means for lowering the support to remove the sole, and connections between the support and said mechanism to stop the operation of the feeding means when the support is lowered.
31. A channeling machine having, in combination, channeling devices, a sole support, sole feeding means, mechanism for operating the feeding means, means for lowering and raising the support, and connections between the support and said mechanism for starting and stopping the feeding means when the support is raised and lowered, respectively.
32. A channeling machine having, in combination, channeling devices; a table for supporting a sole; an edge gage overlying the table; sole feeding means; mechanism for operating the feeding means; means for raising and lowering the table; and connections between said table and mechanism constructed and arranged to start the operation of the feeding means, rendered effective by an engagement of the sole and edge gage, and actuated by raising the table to bring a sole into contact with the channeling devices.
33. A sole-preparing machine having, in combination, feed mechanism, a movable sole support, means controlled by the movement of said support for connecting and disconnecting the power for actuating the feed mechanism, and means for rendering said controlling means ineffective when no sole is in the machine.
34. A channeling machine having, in combination, channeling devices, a sole support, sole feeding means, mechanism for operating the feeding means, means relatively to move the channeling devices and the support to draw them apart in removing a sole, means operated by the relative movement of the support and channeling devices for stopping the said mechanism, and controlling means to prevent starting said mechanism when the channeling devices and support are relatively moved toward one another without a sole on the support.
35. A channeling machine having, in combination, channeling devices, a table for supporting a sole, step-by-step sole feeding devices, mechanism for operating the feeding devices, means for raising and lowering the table to insert and remove soles, means to stop the feeding devices in a predetermined position when the table is lowered to remove a sole, and connections between said table and mechanism for rendering said means effective.
36. A sole-preparing machine having, in combination, sole-preparing devices, a sole support, a four-motion sole feeding device, driving mechanism for the feeding device, means for relatively moving said devices and the support to draw them apart in removing a sole, and means controlled by the relative movement of said devices and the support to stop the driving mechanism at a time when the feeding device is withdrawn from the sole.
37. A channeling machine having, in combination, channeling devices; a support for a sole; sole feeding devices; driving mechanism for the feeding devices; means to relatively move the channeling devices and the support to draw them apart to remove and insert soles, and to move them toward one another to clamp a sole in position to be operated upon; an edge gage mounted to partake of said relative movement; and means connected to said edge gage, and operated by the relative movement of the support and channeling devices, for stopping the driving mechanism when the channeling

devices and support are moved apart, and for starting the driving mechanism when the channeling devices and support are moved toward one another.

5 38. A channeling machine having, in combination, channeling devices, a sole support, sole feeding means, mechanism for operating the feeding means, a clutch for operating the said mechanism, a brake, means relatively to move the support and the channeling devices to separate them in removing and inserting soles, connections between said separating means and the clutch by which said mechanism is stopped and the 10 brake applied when the channeling devices and the support are moved apart, and means to lock said mechanism in position with the brake applied.

20 39. A machine of the class described having, in combination, a work support, means for raising and lowering said support, mechanism controlled by said movements for connecting and disconnecting the power for operating the machine, means for rendering 25 said controlling means ineffective when no work is in the machine, an edge gage, and means operated by the movement of said gage in positioning a sole in the machine for again rendering said controlling means effective.

40 40. A sole-preparing machine having, in combination, sole-preparing devices, a sole support, an edge gage mounted for movement across the table and having a sole 35 guiding position and a sole detecting position, means to raise and lower the support for inserting and removing soles, means to lock the edge gage in a sole guiding position, and means for moving the edge gage into 40 a sole detecting position when the table has been lowered.

45 41. A channeling machine having, in combination, channeling devices, a support for a sole, sole feeding devices, mechanism for operating the feeding devices, means to relatively move the channeling devices and the support to move them away from and toward one another for removing and inserting soles, connections between said means 50 and said mechanism for actuating the feeding devices when the channeling devices and the support are moved toward one another, and an edge gage included in said connections movable from a sole guiding position 55 to a sole detecting position, said gage being constructed and arranged to prevent the actuation of the feeding devices when in its sole detecting position.

60 42. A sole-preparing machine having, in combination, sole-preparing devices, a support for a sole, means for raising and lowering the support for inserting and removing soles, sole feeding devices, mechanism for operating the feeding devices, connections 65 between said mechanism and the support

through which the operation of the feeding devices is started and stopped when the support is raised and lowered, respectively, an edge gage included in said connections, means tending continually to move the edge 70 gage from a sole guiding to a sole detecting position thereby disconnecting the support from said mechanism, and means for locking the edge gage in a sole guiding position 75 operating to prevent a movement of the edge gage to its sole detecting position until the operation of the feeding devices has been stopped.

80 43. A sole-preparing machine having, in combination, sole-preparing devices, a table for supporting the sole, means for raising and lowering the table, sole feeding devices, mechanism for operating the feeding devices, a clutch for said mechanism, a clutch shifting lever, a locking toggle connected 85 with the lever, a connecting lever connected to the toggle, an edge gage pivoted to the table and having an arm movable into and out of a throat in the connecting lever, a plunger for locking the edge gage arm in 90 said throat, and means for removing the arm from said throat when the edge gage, by lowering the table, is moved down below the end of the plunger.

95 44. A machine of the class described comprising, in combination, a work support, means for operating upon and feeding work on the support, mechanism for operating said means, a device for lowering the work support, and a connection from the work support for stopping the operation of said mechanism.

100 45. A machine of the class described comprising, in combination, a work support, means for operating upon and feeding work on the support, mechanism for operating said means, a device for raising the work support, and a connection from the work support for starting the operation of said mechanism.

105 46. A machine of the class described comprising, in combination, a work support, means for operating on work on the support, driving mechanism for said means including a stopping and starting device controlled by separation and approach of the work support and the operating means, and a safety connection controlled by engagement with work on the support to render said device effective when work is in the 110 machine and ineffective when there is no work in the machine.

115 47. A machine of the class described comprising, in combination, a work support, means for operating on work on the support, driving mechanism for said means including a stopping and starting device and a clutch controlled by separation and approach of the work support and the operating means to throw the clutch in at the be- 120 125 130

ginning of an operation and out at the end, and a safety connection including a member engaging work on the support to render said device effective when work is in the 5 machine and ineffective when there is no work in the machine.

48. A machine of the class described comprising, in combination, a work support, a device for operating on work on the support and power driving mechanism therefor, a treadle and connections therefrom for bringing the support and said device together to facilitate placing work in the machine, and auxiliary connections from 10 the treadle including a work-engaging member and means controlled by engagement of the work by said member to render the auxiliary connection effective for connecting the driving mechanism to start the operation of said device when the treadle is 15 raised.

49. A machine of the class described comprising, in combination, a work-support, a device to feed work thereover and mechanism for operating it, a clutch for controlling said mechanism, a brake, means for separating the work-support and said device, connections from said separating means to throw out the clutch and apply the brake, 20 and means to lock said mechanism with the brake applied.

50. A machine of the class described comprising, in combination, a work-support, a device to feed work thereover, and mechanism for operating it, a clutch for controlling said mechanism, means for separating the work-support and said device, connections from said separating means to throw out the clutch, and means to lock said mechanism with the clutch out.

51. A machine of the class described comprising, in combination, a work support, an edge gage mounted for movement across the support and having a work-guiding 45 position and a work-detecting position, operating mechanism and a stopping and starting device therefor, and connections from the edge gage for controlling the operation of the stopping and starting device to prevent operation of said mechanism 50 unless there is work in the machine.

52. A machine of the class described comprising, in combination, a work support, an edge gage mounted for movement relatively 55 to the support and having a work-guiding position, and a work-detecting position, operating mechanism and a stopping and starting device therefor, connections from the edge gage for controlling the operation 60 of the stopping and starting device to prevent operation of said mechanism unless there is work in the machine, and a latch to hold the edge gage in work-guiding position during the operation of the machine.

53. A machine of the class described com-

prising, in combination, operating means and drive mechanism therefor, a treadle and connections therefrom to stop and start said mechanism, an edge-gage movable from a work-detecting to a work-guiding position, and means controlled by movement of the edge gage by engagement with the work for rendering said starting connections effective.

54. A machine of the class described comprising, in combination, operating means and drive mechanism therefor, manually-operable connections to stop and start said mechanism, an edge-gage movable from a work-detecting to a work-guiding position, 70 means controlled by movement of the edge gage by engagement with the work for rendering said starting connections effective, and a latch to hold the edge gage in work-guiding position during the operation of 75 the machine.

55. A machine of the class described comprising, in combination, a device for operating on a piece of work and drive mechanism therefor, stopping and starting means and a controlling arm therefor, a manually-movable member for moving the arm to start the drive mechanism, and safety connections including a member moved by insertion of a piece of work and a part moved thereby 90 to connect the manually-movable member and the arm to permit the drive mechanism to be started.

56. A machine of the class described comprising, in combination, a device for operating on a piece of work and drive mechanism therefor, a clutch and a controlling arm for throwing it into operation, a treadle for moving the arm to throw the clutch, and safety connections including a gage moved 100 by engagement with an inserted piece of work and a part moved thereby to connect the treadle and the arm to throw the clutch into operation and to leave it idle if there 105 is no work in the machine.

57. A channeling machine comprising sole-channeling means, intermittently-operable feeding means, drive mechanism for the feeding means, and operator-controlled means for stopping the operation of the 110 drive mechanism at a predetermined time in its cycle of operation.

58. A machine of the class described comprising, in combination, a work support, operating means and drive mechanism therefor, stopping and starting mechanism controlled by movement of the work-support, and means to predetermine the time of stopping regardless of the time of movement of 115 the work support.

59. A channeling machine having, in combination, channeling devices of the drag knife type; a pair of feeding devices, one at each side of the sole, arranged to grip the sole in the rear of the channeling devices;

- and means for causing the feeding devices to grip the sole and then both move in a right line away from the channeling devices to pull the sole past the channeling devices.
- 5 60. A channeling machine having, in combination, channeling devices, a reciprocable support for the work, a feed foot cooperating with the support to grip the work, said support and said feed foot being arranged 70 to move toward and from the cutting edges of the channeling devices, means to move the support and feed foot in unison in one direction to pull the work against the channeling devices and thereafter to move said support and foot in another direction preparatory to imparting another movement to the work to feed the sole, and toggle mechanism for lowering the support for removing and inserting soles.
- 10 61. A channeling machine having, in combination, channeling devices of the drag knife type, and feed mechanism beyond said devices in the line of feed, constructed and arranged to intermittently grip the work 80 and pull it against the channeling devices.
- 15 62. A channeling machine having, in combination, channel and edge knives, a gage for each knife, in advance thereof, bearing on the stock to be cut by said knives and on the between substance, and a feeding device operating between said knives and in the rear of said gages.
- 20 63. A channeling machine having, in combination, channeling devices of the drag knife type, a work supporting table, a feed slide in the table, a feed foot co-operating with the slide for gripping the work, and means to reciprocate the slide and feed foot to feed the work.
- 25 64. A channeling machine having, in combination, channeling devices of the drag knife type, a work supporting table, a feed slide in the table, a feed foot co-operating with the slide for gripping the work, means 90 to reciprocate the slide and feed foot to feed the work, and mechanism for varying the amplitude of reciprocation of both the slide and feed foot to vary the speed of work feed.
- 30 65. A channeling machine having, in combination, a channel knife, a channel knife presser gage, an edge knife, an edge knife presser gage, a sole supporting table, a feed slide in the table, a feed foot co-operating with the slide to engage the between substance and reciprocate toward and away 95 from the cutting edges of the knives to feed the sole by pulling it against the knives, and means for reciprocating the slide and feed foot.
- 35 66. A channeling machine having, in combination, channeling devices of the drag knife type, a sole supporting table, a feed slide mounted in the table, a feed foot carrier pivotally mounted in the frame, a slide 100
- in said carrier having a feed foot thereon which is located opposite the feed slide, a connection between said carrier and the feed slide, means to reciprocate the carrier, and means for reciprocating the feed foot slide 75 to clamp the feed foot to and release it from the sole during the feed and return strokes respectively of the carrier.
- 40 67. A channeling machine comprising, in combination, a horizontal sole-supporting table, and channeling and feeding means including a device mounted to oscillate in a vertical plane about a horizontal axis below the table and an overhanging sole-engaging portion slidingly and yieldingly mounted in 80 said device.
- 45 68. A channeling machine comprising, in combination, a horizontal sole-supporting table, and channeling and feeding means including a device mounted to oscillate in a vertical plane about a horizontal axis below the table and having a sole-engaging portion 85 overhanging said table.
- 50 69. A channeling machine comprising, in combination, a sole support, and channeling and feeding means including a device mounted to oscillate transversely in a vertical plane about a horizontal axis below the sole support and having a work-engaging part 90 overhanging the support, a constantly-oscillated slotted drive arm, a link connected to said device and a block pivoted on the link and mounted in the slotted arm, and a treadle and connections therefrom for moving the block in said arm to vary under control of an operator the amplitude of the oscillations of said device.
- 55 70. A channeling machine comprising, in combination, a sole support, and channeling and feeding means including a device mounted to oscillate transversely in a vertical plane about a horizontal axis below the sole support and having a work-engaging part 100 overhanging the support, a constantly-driven member, and operator-controlled connections from said member to said device for varying the amplitude of the oscillations of said device.
- 60 71. A sole-preparing machine comprising, in combination, a sole support, an arm mounted to oscillate transversely of the support in a vertical plane about a horizontal axis below the support, and a sole-engaging feed member slidingly mounted in said arm intermittently to feed a sole over the support.
- 65 72. A sole-preparing machine comprising, in combination, a sole support, an arm mounted to oscillate transversely of the support in a vertical plane about a horizontal axis below the support, and a sole-engaging feed member mounted in said arm overhanging the support intermittently to feed a sole thereover.
- 70 73. A sole-preparing machine comprising 115

ing, in combination, a sole support, an arm mounted to oscillate transversely of the support in a vertical plane about a horizontal axis below the support, a feed member carried by the arm, a drive shaft parallel to the axis of oscillations of said arm having an eccentric thereon, and connections from the shaft to said arm including a slotted lever and a pair of links connected respectively to 5 said arm and the eccentric, one of the links being connected to the lever and the other having a part to slide therein to vary the feed.

74. A sole-preparing machine comprising, 15 in combination, a sole support, an arm mounted to oscillate transversely of the support in a vertical plane about a horizontal axis below the support, a feed member carried by the arm, a drive shaft having a drive member thereon, and connections from the shaft to said arm including members relatively movable under the control of an operator to vary the amplitude of oscillation of said arm.

20 75. A sole-preparing machine comprising, in combination, a sole support, a four-motion feed foot, a drive shaft and connections therefrom to raise and lower the feed foot, an arm mounted for oscillation about a horizontal axis below the support and separate connections from the shaft for oscillating it, and a connection between the arm and the feed foot for oscillating the feed foot.

25 76. A sole-preparing machine comprising, in combination, a sole support, a four-motion feed foot intermittently to feed a sole there-over, a drive shaft and a pair of eccentrics thereon, a link connected to one eccentric to raise and lower the feed foot, an arm mounted for oscillation about a horizontal axis below the support and separate link connections from the other eccentric for oscillating it, and a connection between the arm and the feed foot for oscillating the feed foot.

30 77. A sole-preparing machine comprising, in combination, a sole support, a four-motion feed foot intermittently to feed a sole there-over, a drive shaft and a pair of eccentrics thereon, a link connected to one eccentric to raise and lower the feed foot, an arm mounted for oscillation about a horizontal axis below the support and separate link connections from the other eccentric for oscillating 35 it, a connection between the arm and the feed foot for oscillating the feed foot, and operator-controlled means for varying the link connections to said arm for varying the amplitude of oscillation of the feed foot without affecting the amplitude of its upward and downward motions.

40 78. A machine of the class described comprising, in combination, a horizontal work-support, and a device mounted for transverse oscillation in a vertical plane about a hori-

50 zontal axis below the support intermittently to feed work over the support.

79. A machine of the class described comprising, in combination, a horizontal work-support, a device mounted for transverse oscillation in a vertical plane about a horizontal axis below the support, and a feed foot slidingly mounted in said device intermittently to feed work over the support. 70

80. A machine of the class described comprising, in combination, a horizontal work-support, a device mounted for transverse oscillation in a vertical plane about a horizontal axis below the support, a feed foot slidingly mounted in said device intermittently to feed work over the support, and operator-controlled means for varying the amplitude of oscillation of said device to change the rate at which the work is fed. 75

81. A channeling machine having, in combination, a channeling device, a table for supporting a sole, an edge gage adjustable across the face of the table, a slide for the edge gage mounted on the table, and means for adjusting the slide. 85

82. A channeling machine having, in combination, a channeling device, a table for supporting a sole, an edge gage adjustable across the face of the table, a slide for the edge gage mounted upon the table and having an eccentric adjusting block, a hand lever for moving the block, a plurality of latch plates mounted upon the table, and a plurality of latches on the hand lever co-operating with the locking plates to lock 90 the edge gage in different positions. 95

83. A channeling machine having, in combination, a channel knife, a slide carrying said knife, an edge knife, a slide carrying said knife, an edge presser gage, a slide carrying said gage, a sole support, and means by which the slides may be simultaneously or separately moved away from the support while the machine is operating upon a sole. 100

84. A channeling machine having, in combination, a channel knife, a slide carrying said knife, an edge knife, a slide carrying said knife, a sole support, means for lowering the support, and treadle operated means by which the slides may be simultaneously or separately moved away from the support independently of the operation of the support. 105

85. A channeling machine having, in combination, a channel knife, a slide carrying said knife, an edge knife, a slide carrying said knife, a sole support, means for lowering the support, connections between the support operating means and the slides by which the slides may be simultaneously or separately raised when the support is lowered, and independently operated means by which the slides may be simultaneously or separately moved away from the support. 115 120 125 130

86. A channeling machine having, in combination, channeling devices, a sole support, means for relatively moving the channeling devices and the support to permit the removal of the sole, sole feeding means, and means controlled by the relative movement of the channeling devices and the support to stop the sole feeding means at a predetermined time in its cycle of movement. 25
87. A channeling machine having, in combination, channeling devices, a sole support, means for relatively moving the channeling devices and the support to permit the removal of the sole, sole feeding means, a clutch to transmit power to the sole feeding means, and means controlled by the relative movement of the channeling devices and the support to render the clutch inoperative in timed relation with the movements of the sole engaging instrumentalities. 30
88. A channeling machine having, in combination, channeling devices, a movable work support, a movable edge gage, power actuated means for causing said devices to cut a channel in the sole, and means rendered operative by the movement of the edge gage for controlling the application of power to the machine by the movement of the work support. 35
89. A channeling machine having, in combination, a machine frame, an edge knife slide movably mounted on the frame and provided with an edge slitting knife, an edge presser gage slide movably mounted on the frame independent of said edge knife slide and provided with a presser gage, a knife mounted on the presser gage slide arranged to co-operate with the edge slitting knife to form a shoulder, and means for connecting said slides at the will of the operator to cause them to move in unison and gage both cuts from the same side of the sole during the operation of the machine. 40
